UNITED STATES PATENT OFFICE

167,193

EYESHADE OR SIMILAR ARTICLE

Robert A. Bruce, New Hyde Park, N. Y.

Application March 8, 1951, Serial No. 14,432

Term of patent 14 years

(Cl. D57—1)

To all whom it may concern:

Be it known that I, Robert A. Bruce, a citizen of the United States, residing at 139 Laurel Drive, New Hyde Park, Long Island, New York, have invented a new, original, and ornamental Design for an Eyeshade or Similar Article, of which the following is a specification, reference being had to the accompanying drawing, constituting a part hereof.

Fig. 1 is a bottom perspective view of the eye shade or similar article showing my new design;

Fig. 2 is a bottom plan view;

Fig. 3 is a front elevational view;

Fig. 4 is a rear elevational view; and

Fig. 5 is a side elevational view.

I claim:

The ornamental design for an eye shade or similar article, substantially as shown.

ROBERT A. BRUCE.
